FIG. 1 is a rear perspective view of a base station for a tissue treatment system;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

In the drawings, the even dash-dot broken lines are for the purpose of illustrating portions of the base station for a tissue treatment system that form no part of the claimed design. The dash-dot lines are for the purpose of illustrating the claim boundaries and form no part of the claimed design.
